UNITED STATES PATENT OFFICE.

DE SOTO LOVEJOY, OF MOSCOW, TEXAS, ASSIGNOR OF ONE-HALF TO SOLOMON BERGMAN AND WILLIAM M. KENNEDY.

MOTOR.

SPECIFICATION forming part of Letters Patent No. 402,172, dated April 30, 1889.

Application filed November 23, 1888; Serial No. 291,673. (No model.)

To all whom it may concern:

Be it known that I, DE SOTO LOVEJOY, a citizen of the United States, residing at Moscow, in the county of Polk and State of Texas, have invented new and useful Improvements in Motors, of which the following is a specification.

My invention relates to improvements in motors; and it consists in certain novel features, hereinafter described and claimed.

In the accompanying drawings, Figure 1 is a side view of a motor embodying my invention. Fig. 2 is a front view of the same.

Referring to the drawings by letter, A designates a chair of the usual or any preferred construction. In the seat *a* of the chair, at the center of the same, I form a guide-opening, B, through which passes a vertical post or bar, C, having a rest or secondary seat, D, secured to its upper end. The said seat D is provided on its under side with the depending guides E, which project downward through suitable openings in the seat *a* of the chair, and thereby secure a true vertical movement of the rest and the bar C. A spring, F, is coiled around the upper portion of the bar C, between the chair-seat and the rest D, to return the said rest to its normal position after having been depressed. If so desired, additional springs may be placed around the guides E, to aid the spring F in returning the said rest to its normal position.

G designates a transverse shaft, journaled in suitable bearings secured to the legs of the chair and having mounted thereon, in front of the bar C, a drum, H. This drum H is provided with a transverse opening, I, through which passes a portion of a cord, J, the main part of said cord being coiled around the said drum, as shown. From its coiled portion this cord extends rearward across the lower end of the bar C, fitting in a notch, K, therein, and thence extends upward to a transverse perforation, L, in the said bar, near its upper end, and thence through said perforation, and downward again through the drum. The cord is drawn taut around the bar C and the drum, so that when the said bar is being lowered the cord

will be unwound, thereby rotating the drum in one direction, and when the bar is being raised the cord will wind on the drum, thereby rotating said drum in the opposite direction.

The drum is provided at one end with a ratchet-wheel, M, and on the shaft G, adjacent to said ratchet-wheel, is mounted a gear-wheel, N, to the side of which is pivoted a pawl, O, adapted to engage the ratchet-wheel M, and held normally in engagement with said ratchet-wheel by a spring, P, having one end secured to the side of the wheel N and its other end bearing on the pawl, as clearly shown.

In operation the operator sits upon the platform or rest D, or places a weight thereon, thereby depressing the same against the spring F, thereby causing the bar C to descend and rotate the drum so as to set the gear-wheel N in motion and thereby operate the machinery to which the said gear-wheel is geared. When the rest D has reached the lowest limit of its movement, the weight is removed therefrom, and the spring F then returns it to its former elevated position, thereby raising the bar C and rotating the drum in the opposite direction, and winding the cord thereon, so that upon the next downward movement of the bar C the drum will be again rotated to operate the gear-wheel. It will be observed that the pawl is so arranged as to allow the teeth of the wheel M to slip past when the bar C is being raised, so that the gear-wheel N will not be driven backward. Upon the downward movement of the said bar, however, the ratchet-wheel engages the pawl so as to operate the machinery driven.

It will be observed that my device is very simple, is composed of few parts, and the said parts are compactly arranged. The device is especially adapted for running light machines—such as sewing-machines, churns, and fans—and its advantages are thought to be obvious.

Having thus described my invention, what I claim and desire to secure by Letters Patent, is—

The combination of the chair, the recipro-

cating bar, the shaft mounted in the lower portion of the chair, the drum on said shaft, the cord coiled around the drum and connected to the bar, the rest secured to the upper end 5 of the bar, and the spring coiled around the said bar between the chair-seat and the rest, as specified.

In testimony that I claim the foregoing as my own I have hereto affixed my signature in presence of two witnesses.

DE SOTO LOVEJOY.
